(57) CLAIM

The ornamental design for an elevated dog bowl having an open front, as shown and described.

DESCRIPTION

FIG. 1 is a top perspective view of an elevated dog bowl having an open front.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The broken lines illustrate portions of the elevated dog bowl having an open front that form no part of the claimed design.
